UNITED STATES PATENT OFFICE.

JAMES H. BERRY, OF YONKERS, NEW YORK, ASSIGNOR TO ALEXANDER SMITH & SONS CARPET COMPANY, OF YONKERS, NEW YORK, A CORPORATION OF NEW YORK.

DESIGN FOR A CARPET.

60,506.

Specification for Design.

Patented Mar. 7, 1922.

Application filed December 7, 1921. Serial No. 520,726. Term of patent 14 years.

To all whom it may concern:

Be it known that I, JAMES H. BERRY, a citizen of the United States, residing at Yonkers, county of Westchester, State of New York, have invented a new, original, and ornamental Design for a Carpet, of which the following is a specification, reference being had to the accompanying drawing, forming a part thereof.

The figure is a face view of a portion of a carpet showing the design.

The design is intended to be worked into or upon a carpet or similar fabric in such colors as may be desired.

I claim:

The ornamental design for a carpet or similar fabric, substantially as shown.

JAMES H. BERRY.
